ELECTROMAGNETIC DEFLECTION SYSTEM

Peter Johannes Hubertus Janssen and Johan Anton Verhoef, Eindhoven, Netherlands, assignors, by mesne assignments, to North American Philips Company, Inc., New York, N.Y., a corporation of Delaware

Application August 16, 1955, Serial No. 528,690

Claims priority, application Netherlands September 1, 1954

5 Claims. (Cl. 315—27)

This invention relates to deflection coil systems for electrical apparatus.

An known electromagnetic deflection system for deflecting an electron beam in two directions at right angles to each other comprises four coils wound toroidally on a cylindrical core of ferromagnetic material for deflection in one of the directions. The first and the third coils are diametrically opposed and connected in parallel with one another, and the second and fourth coils are also diametrically opposed and connected in parallel with one another, while the two parallel combinations are connected in series with one another. Deflection systems of this kind are employed in television systems, in which use is made of coils wound in different senses, which entails additional expense during the manufacture.

It is an object of the invention to provide an electromagnetic deflection system in which this disadvantage is obviated.

It is a further object of the invention to provide a deflection system wherein the polarity of the stray voltages which are induced in each coil by the coils producing deflection in the perpendicular direction is such as to prevent difficulties with respect to insulation of the coils from the core of the system.

The system in accordance with the invention is characterized by the four coils being wound identically, with the first and fourth coils being mounted on the core in the same manner, whereas the second and the third coils being provided on the core in the opposite manner to the first and fourth coils.

An embodiment of the deflection system in accordance with the invention and its further advantages will now be described with reference to the accompanying drawing, in which:

Fig. 1 shows an embodiment of a system according to the invention for deflection in two directions;

Fig. 2 shows a part of the system illustrated in Fig. 1 in which four toroidal coils are employed to effect the required deflection;

Figs. 3a and 3b are plan and side views respectively of a coil employed in the system illustrated in Fig. 2;

Fig. 4 shows the manner in which the coils of Figs. 2 and 3 are provided on the core and how they are connected to one another and to the supply-source;

Fig. 5 shows an electric circuit arrangement including the system of the invention and the interconnections between the different parts of the deflection system.

In Fig. 1, there is provided a cylindrical annular core 5 made of ferromagnetic material, for example, the ferromagnetic ferrites, which core usually consists of two parts in order to enable coils to be mounted thereon. Four toroidal coils 1, 2, 3 and 4 surround the core 5, which coils in combination furnish the deflection in the vertical direction for, for example, an electron-beam in a cathode-ray tube. In Fig. 1, only the glass wall 6 of the tube neck is shown. The coils 1 and 3 are mounted diametrically opposite one another, as are the coils 2 and 4. In the embodiment shown, the part of the de-

2

fection system for the horizontal deflection consists of two saddle-shaped coil halves 7 and 8, the operative parts of which extend at right angles to the plane of the drawing at 9, 10, 11 and 12 and are arranged within the annular core 5. The ends of said operative parts of each coil-half are interconnected by parts 13 and 14. The latter parts usually closely surround the circumference of the tube-neck 6; here, however, for convenience, they are shown bent outwards so that the coils 1, 2, 3 and 4 may be seen.

In Fig. 2, in which parts corresponding to Fig. 1 are designated by like reference numerals, the part of the system for deflection in the horizontal direction is not shown. However, the path of the magnetic flux for the horizontal deflection at a given instant of time is shown by means of lines 15 and 16 and the associated arrows. Likewise, the direction of the flux for vertical deflection, which flux is produced by the coils 1, 2, 3 and 4, is shown by double arrows 17 and 18. From the path of the flux, it will be seen that the horizontal and vertical fluxes have the same direction in the coils 2 and 4, and the opposite direction in the coils 1 and 3.

If, now, the coils 1 and 3 are connected in parallel with one another, the electromotive force which is induced in the thus produced closed circuit by the horizontal flux is zero, since the fluxes are in opposite directions in these coils, so that in this circuit no troublesome circulating currents will flow. The same applies to the parallel combination of the coils 2 and 4 with respect to the horizontal flux. If, now, the two parallel combinations are connected in series with one another, in this series circuit an electromotive force is also not induced by the horizontal flux. This will be seen from reference to Fig. 5, in which the circuit arrangement of the coils 1, 2, 3 and 4, which are shown as inductance coils, is shown and in which the polarity of the electromotive force induced in each coil by the horizontal flux is indicated by plus and minus signs. Thus, in the closed circuits 1, 3 and 2, 4, no electromotive force is induced at all, and in the series connection of the circuits 1, 3 and 2, 4 the induced electromotive forces will also cancel each other.

Fig. 3a is an elevation of a coil such as those illustrated in Fig. 2 and designated 1, 2, 3 or 4. The core 5, not shown, passes through the aperture 19. The turns of the coil are wound in several layers and, for the sake of clearness, the end or starting turn 20 situated in the bottom or inner layer is shown by a broken line, while the other end or terminal turn 21 situated in the outer or top layer is shown by a full line. The same applies to Fig. 3b, which shows a side elevation of the coil. In the latter figure, the end 20 shown by the broken line is arranged on one side and the end 21 shown by the full line is arranged on the other side of the core, with a view to a better understanding of Fig. 4 in which these ends are shown in the same manner.

Fig. 4 shows the manner, in the system in accordance with the invention, in which the coils are supported from the core 5, which is shown in developed form. The coils 1, 2, 3 and 4 are identical and consequently wound identically. The coils 1 and 4 are mounted on the core in the same manner, both having the end or starting turn situated in the bottom layer of the coil at the left hand side in the drawing.

The orientation of the coils 2 and 3 is also the same but they are rotated through 180° relative to the coils 1 and 4, so that the ends or starting turns of the coils 2 and 3 situated in the bottom layer are at the right-hand side in Fig. 4. In addition, the coils 1 and 3 are connected in parallel with one another, as has been mentioned above, in that the ends thereof situated in the bottom layers on the one hand, and the ends situated in

the top layers on the other hand, are connected to one another. Corresponding ends of the coils 2 and 4 are also connected to one another so that they are also in parallel, while corresponding ends, i.e. ends situated in the upper layer, of the coils 1 and 3 are also connected to the same ends of coils 2 and 4, so that these four ends in the outer layers of all the coils have the point P shown in Fig. 4 in common. By means of a terminal A, a supply source 22 of vertical deflection (sawtooth) current is connected to the end in the bottom layers of coils 1 and 3, while a terminal B of the source 22 is connected to the ends in the bottom layers of coils 2 and 4. The direction of the deflection current at a given instant in the various coils is shown by arrows.

In Figure 5 the circuit arrangement is shown corresponding to the configuration set out in Fig. 4. The points A, B and P are also shown therein. As has been mentioned hereinbefore, the polarity of the electro-motive force which is generated in the coils 1, 2, 3 and 4 by the horizontal flux is indicated at each coil. While these generated voltages do not produce troublesome circulating currents, due to the fact that each coil has an associated inherent capacitance, which is shown in the figure by C_1 , C_2 , C_3 and C_4 , a further difficulty would arise, since, without further expedients, another stray oscillation would occur in the entire vertical deflection circuit on termination of the flyback voltage of the horizontal deflection current. This stray oscillation can be substantially rejected by connecting the mid-point of the vertical deflection coil system, i.e., the point P, via a capacitor C_5 to a point of the horizontal deflection system at which, during the occurrence of the flyback, a voltage pulse is produced.

In Fig. 5 the horizontal deflection arrangement is shown diagrammatically by a sawtooth current generator 23 of known design which, through a transformer 24, feeds the horizontal deflection coils 25. One side of the deflection arrangement is connected in known manner to a point of constant potential, e.g. ground, as is also the case with one of the terminals of the vertical deflection arrangement. The point P is connected via the capacitor C_5 to a point of which the potential varies intensely during the fly-back of the generator 23, for example, to the upper end 26 of the coil 25 or, in the alternative, to the upper end of the primary of the transformer 24.

Assuming the amplitude of the pulse voltage which is induced in each vertical coil to be E_1 , the amplitude of the fly-back pulse voltage at the point 26 to be E_2 , the total capacitance produced in the vertical deflection circuit to be C , and the capacitance of the coupling capacitor C_5 to be C_5 , in the vertical deflection circuit no troublesome stray oscillations will occur provided that C_5 is selected so that

$$C_5 = C \frac{1}{\frac{E_2}{E_1} - 1}$$

An important advantage of the deflection coil system in accordance with the invention is that the point P, which due to the induced voltage is continually at a high potential, is connected to the ends situated in the outer layers of the coils. The voltage of the ends situated in the bottom or inner layers varies only slightly. This is of advantage since these bottom layers are close to the core 5, and it is undesirable for a high voltage to be produced across the insulation to the core.

While we have described our invention in connection with specific embodiments and applications, other modifications thereof will be readily apparent to those skilled in this art without departing from the spirit and scope of the invention as defined in the appended claims.

What is claimed is:

1. An electromagnetic deflection system comprising a substantially cylindrical ferromagnetic core, and on said

core four identically-toroidally-wound coils arranged in order, the first and third coils being diametrically opposed to one another and electrically connected in parallel, the second and fourth coils being diametrically opposed to one another and electrically connected in parallel, the two parallel combinations of coils being electrically connected in series, the first and fourth coils being mounted on the core in the same manner such that their windings begin and end in the same way, the second and third coils being mounted on the core in positions rotated 180° relative to said first and fourth coils.

2. A deflection system as claimed in claim 1 in which the four coils are wound in several layers of turns, the ends of the four coils which are connected to one another being all situated in the outer layers.

3. An electromagnetic deflection arrangement comprising a cylindrical ferromagnetic core, horizontal and vertical deflection coil systems mounted adjacent said core, one of said systems being wound on said core and comprising four identically-toroidally-wound coils arranged in order and each of said coils comprising inner and outer layers with ends secured respectively thereto, the first and third coils and the second and fourth coils being connected in parallel, the two parallel combinations being connected in series, the second and third coils being positioned on said core such that their windings begin and end in the same way, the first and fourth coils being located on said core in positions rotated 180° relative to that of the second and third coils, the ends connected to the outer layers of the four coils being interconnected.

4. An electromagnetic deflection arrangement as set forth in claim 3 including means for generating a voltage pulse in producing the deflecting current for the other of said systems, and means capacitatively coupling said interconnection of the outer turns of the four coils to said generating means.

5. An electromagnetic deflection arrangement comprising a substantially cylindrical ferromagnetic core, four coils mounted on and enclosing a section of said core and arranged such that the first and third coils are diametrically opposed to one another, and the second and fourth coils are diametrically opposed to one another, all of the coils being identically wound and comprising plural layers of turns with a starting turn at one side in the innermost layer and a terminal turn at the opposite side in the outermost layer, means connecting together the starting and the terminal turns of the first and third coils so that a parallel connection exists, means connecting together the starting and the terminal turns of the second and fourth coils so that they too are connected in parallel, means connecting together in series relationship the two parallel coil combinations, and means for feeding deflection currents to the serially-connected coil combinations, the four coils being mounted on the cylindrical core in the following manner: the first coil has its starting turn facing to one side, the second coil has its starting turn facing to the opposite side, the third coil has its starting turn facing to the same side as the first coil, and the fourth coil has its starting turn facing to the same side as the second coil, whereby the positioning of the second and third coils on the core is opposite to that of the first and fourth coils.
